UNITED STATES PATENT OFFICE

LUIGI MAGRINI, OF BERGAMO, ITALY

OIL SWITCH

Application filed December 23, 1928, Serial No. 156,673, and in Germany February 18, 1928.

This invention relates to improvements in oil switches or interrupters.

Oil switches are known in which differentially distributed cavities are arranged and communicate with the interior of a reservoir, thus allowing the gases produced by the decomposition of the oil to expand. These expansion chambers constitute sometimes a separate space above the oil surface to which the gases of decomposition are led.

Switches are also known in which the said gases are led to the exterior by suitable communications and, again, arrangements are known which pass a current of oil to the part where the arc forms, for the purpose of quenching the latter.

Heretofore, however, these three features have not been embodied in a single switch, and the practical embodiments hitherto proposed of each of the three features have actually been of a nature such as to exclude the other two.

This invention has for its object to provide an oil switch in which the three above mentioned features exist together, and it is characterized in that the movable contact or contacts of the switch are carried by a plunger or piston which creates in its upward stroke a space, the volume of which increases proportionally to and simultaneously with the production of the gases of decomposition of the oil.

Since the dimensions and the speed of displacement of the piston can be selected in such a way that the expansion space or chamber is always equal to or greater than the volume of gas produced by the decomposition of the oil, the pressure of the gas will never exceed that of the atmosphere and consequently the pressure of the gas will never function to displace the piston, nor discharge the gas. In fact, these dimensions can be calculated for the extreme case when the switch is opened under short-circuit. Consequently under more favourable circumstances, where the production of the gas is less, a partial vacuum will be produced in the interior of the chamber of the switch and the gases will only be discharged to the exterior during the descending stroke of the piston

which will compress them in the upper part of the chamber of the switch above the level of the oil.

In the accompanying drawing, the single figure represents by way of example a vertical section of a device for carrying out the invention and incorporating the aforesaid three features.

The essential feature of this device is that the plunger or piston is hollow and filled with oil and is provided at its lower end with small openings which allow the oil to flow slowly into the reservoir as soon as the pivot is raised, in order to fill the said reservoir completely and consequently prevent the formation of an air space. A check valve is disposed in the gas outlet pipe to prevent the entrance of air into the reservoir.

A cylindrical body 1 fixed to the base 3 and to the cover 4 forms the reservoir 2 in which moves a plunger or piston 8. The piston is hollow and is provided with a rod 8¹ which is also hollow, the interiors of both the piston and rod being in communication with one another and with the atmosphere through the end of the rod. The piston is provided with a contact 5¹, of which the corresponding contact 5 is carried by the base 3, and is also provided with small openings 5² for the discharge of the oil. The cover 4 is provided at its highest part with a pipe 4¹ for the discharge of the gases, which are led to the atmosphere by the pipe 4².

A non-return valve 16 of any known type prevents the entrance of air even when there is a partial vacuum within the reservoir. A pipe 15 puts the interior 17 of the cylinder 18 in which is disposed the rod 8¹ into communication with the outlet 4². The cylinder 18 forms a guide for the rod 8¹ and for the piston while allowing the oil contained in the chamber 17 to descend to the lower chamber 2.

The operation is believed to be apparent from the above description. The principal feature is the use of the hollow piston and rod and in the provision of the small openings 5² at the bottom of the piston. The oil in the reservoir fills the chambers 2, 4¹, 4² and 17 and the interiors of the piston 8 and

- of the rod 8¹ up to the level A—A¹. When the piston is raised rapidly it functions as a solid piston. If it is raised slowly or left in its upper position the oil issuing through the small openings 5" completely fills the chambers of the apparatus. This arrangement, in cooperation with the non-return valve 16, completely eliminates the formation of air spaces in the apparatus and consequential defects.
- 10 The shape and arrangement of the various parts of the apparatus obviously can be varied according to necessity without departing from the scope of the invention.
- 15 Having now particularly described and ascertained the nature of my invention and in what manner the same is to be performed I declare that what I claim is:
1. In an oil switch, the combination of an oil reservoir, a contact within the reservoir fixed to the bottom thereof, a hollow piston movable vertically within the reservoir and having a plurality of ports at its lower end to enable oil to enter and fill the piston when the latter is lowered and to escape from the piston when raised, a hollow rod or stem connected to the piston and communicating with the interior thereof and with atmosphere, and a contact fixed to the lower end of the piston for coaction with the first contact; said piston creating within the reservoir during its upward movement a gas space having at least the same volume as that of the gases produced by decomposition of the oil.
2. In an oil switch, the combination of an oil reservoir, a contact within the reservoir fixed to the bottom thereof, a hollow piston movable vertically within the reservoir and having a plurality of ports at its lower end to enable oil to enter and fill the piston when the latter is lowered and to escape from the piston when raised, a hollow rod or stem connected to the piston and communicating with the interior thereof and with atmosphere, a contact fixed to the lower end of the piston for coaction with the first contact, an outlet pipe for the gases of decomposition of the oil having its mouth below the level of the oil when the switch is closed but uncovered when the oil level drops consequent on the upward movement of the piston, and a check valve in said outlet pipe for preventing entrance of air into the reservoir consequent on the partial vacuum produced therein during such upward movement; said piston creating within the reservoir during its said upward movement a gas space having at least the same volume as that of the said gases.
3. In an oil switch, the combination of a reservoir provided with a gas outlet and with an internal contact and filled with oil; and a piston having ports at its bottom and provided with a contact for cooperation with the reservoir contact and adapted to plunge

into the oil in such a way as to displace a volume of oil at least equal to that of the gases of decomposition, whereby said piston, during its upstroke, will act to lower the oil level in the reservoir sufficiently to uncover the gas outlet; said piston having a cavity that communicates at top with atmosphere and at bottom by way of said ports with the oil in the reservoir.

In testimony whereof I affix my signature.

LUIGI MAGRINI.
